UNITED STATES PATENT OFFICE.

HENRY FOSS, OF DEER RIVER, MINNESOTA.

PROTECTOR FOR RAILWAY-SWITCHES.

1,307,662.

Specification of Letters Patent. Patented June 24, 1919.

Application filed March 26, 1919. Serial No. 285,205.

To all whom it may concern:

Be it known that I, HENRY Foss, a citizen of the United States, residing at Deer River, in the county of Itasca and State of Minnesota, have invented certain new and useful Improvements in Protectors for Railway-Switches, of which the following is a specification.

This invention relates to improvements in protectors for railway switches. The prime object of the invention is to provide simple means for keeping the rails at the switch points clear of snow, ice and debris in order that the movable switch points may function properly. With the foregoing and other objects in view the invention consists in the combination and arrangement of parts to be hereinafter fully described, pointed out in the appended claims and illustrated in the accompanying drawing which forms a part of this specification and in which—

Figure 1 is a plan view of a railway switch provided with my improved protector.

Fig. 2 is a cross section, enlarged, of Fig. 25 1 on line 2—2.

Fig. 3 is an enlarged fragmentary view of Fig. 2.

Like reference characters denote corresponding parts throughout the several views.

The reference numeral 1 denotes the switch-rails and 2 the main-line rails. To the relatively remote sides of the rails 2 upon the ties 3 I secure by bolts the extensions 4 of the stationary bearings 5 through which the rotary rods or pintles 6 extend that are fast to the sleeves 7 formed integral with the hinge-like cover 8 of inverted trough-like formation, which cover is adapted, in one position, to shelter or cover one switch-rail and one main-line rail at and about their point of engagement with each other. Covers 8 are disposed opposite each other or in pairs to protect both switch points and to shield the same from snow, ice and debris. In operative position the covers 8 have their free lateral edges disposed upon the rail ties. Each pindle 6 is provided at

one end with a bevel gear 9 in mesh with another bevel gear 10 arranged upon a rotary reach rod 11 journaled in bearings 12 50 secured to a tie. Each rod 11 is connected by a terminal bevel gear 13 with another bevel gear 14 fast upon a rotary control-post 15 operable by a handle 16, said control-post, as well as one end of the reach rod 11, being 55 journaled in a frame 17 secured to one railway tie; signal wings 18 carried by the control-post denote the position of the same relative to the frame 17.

By partial rotation of the control-post the 60 reach rod is rotated and the covers 8 raised and lowered, two positions of the same being shown in Figs. 2 and 3. The covers are raised to permit a train to pass the switch after which they are lowered to protect the 65 switch. The switch rails are operated by the usual rod and lever 19, 20.

What is claimed is:

1. In a protector for railway switches, a pair of inverted trough-shaped covers 70 secured to the railway ties upon the relatively remote sides of the rails, and manually operable means for moving said covers simultaneously to cause them to cover and uncover the rails substantially as set forth. 75

2. In a protector for railway switches, a pair of oppositely disposed inverted trough-shaped covers secured to the railway ties upon the relatively remote sides of the rails, pintles operatively secured to said covers, a 80 reach rod, gear-connection between said reach rod and pintles, a control-post gear-connected to said reach rod, and a handle for actuating said control-post and connections. 85

In testimony that I claim the foregoing as my own I have hereto affixed my signature in the presence of two subscribing witnesses.

HENRY FOSS.

Witnesses:

S. J. MORAN,
W. W. RODMAN.
